UNITED STATES PATENT OFFICE.

DANIEL S. WAUGH, OF DENVER, COLORADO, ASSIGNOR TO DENVER ROCK DRILL MANUFACTURING COMPANY, OF DENVER, COLORADO, A CORPORATION OF DELAWARE.

MOTOR.

1,183,257.

Specification of Letters Patent.

Patented May 16, 1916.

Application filed December 19, 1913. Serial No. 807,676.

To all whom it may concern:

Be it known that I, DANIEL S. WAUGH, a citizen of the United States, residing at Denver, in the county of Denver and State of Colorado, have invented new and useful Improvements in Motors, of which the following is a specification.

The present invention relates more particularly to the means for effecting the operation of the piston of a motor of the pneumatic hammer type, and one of the primary objects is to provide a combination of parts, in which the piston may be mounted to operate in a chuck sleeve or similar element that is rotatable, the arrangement being such that the motive fluid is properly supplied to the piston and the distribution of said fluid is made effective, irrespective of the rotation of such sleeve.

20 An embodiment of the invention is illustrated in the accompanying drawings, wherein:

Figure 1 is a longitudinal sectional view through the structure. Fig. 2 is a horizontal sectional view on the line 2—2 of Fig. 1. Fig. 3 is a view that is diagrammatic in its character in order to illustrate the relation of the various passageways and ports, so that the operation of the mechanism may be made clear.

Similar reference numerals designate corresponding parts in all the figures of the drawings.

In the embodiment disclosed, a cylinder member 4 is employed having a bore provided with sections or portions of different diameters, designated respectively 5, 6, and 7, and thereby producing internal shoulders 8 and 9, the portion of smallest diameter being at the front end of the cylinder member, the portion of greatest diameter being at the rear end thereof. In this cylinder is rotatably mounted a chuck, which includes a sleeve having portions or sections 10 and 11 of different diameters, the portion 10 snugly rotating in the bore section 7 of the cylinder member, and the portion 11 fitting the portion 6 of said cylinder bore. This sleeve is held against forward movement by a shoulder 12 that abuts against the shoulder 8 and by a flange 13, which is located in the largest portion 5 of the cylinder bore and co-operates with the shoulder 9. The sleeve is held against rearward movement by a retaining nut 14 on to the projecting end

thereof and bearing against the front end of the cylinder member. This retaining nut serves also to hold in place a chuck bushing 15 having a flange 16 that is interposed between the front end of the sleeve and the head of said nut, being held against rotation by a pin 17. The bushing 15 is provided with an angular socket 18 to receive the shank 19 of a suitable tool.

A reciprocating piston 20 is mounted in the rear portion 11 of the chuck sleeve and is provided with an intermediate annular groove 21 that is intersected by spiral or angular keyways 22 formed in the periphery of the piston and disposed generally longitudinally thereof. These keyways receive the keys or feathers 23 formed upon mechanism that is employed for rotating the chuck. This mechanism is made the subject-matter of a separate application, and it is therefore believed to require no further explanation here. The grooves or keyways 22 are important in the present structure, inasmuch as they constitute means of communication between the piston chamber in rear of the piston and the annular or peripheral groove 21 of said piston.

The cylinder member 4 is formed upon one side with a distributing valve casing 24, the bore of which is provided with a central annular groove 25, and other annular grooves 26 and 27 located on opposite sides thereof. In the bore of the valve casing 24 are placed bushings 28 and 29 having flanges 30 on their outer ends, which abut against the ends of the casing. The inner ends of the bushings 28 and 29 are spaced apart, so as to afford communication with the central groove, and said bushings furthermore have ports 32 and 33 communicating respectively with the side grooves 26 and 27. A passageway 34 leads from the rear end of the cylinder member to the annular groove 26, and another passageway 35 leads from the groove 27 to an annular channel 36 formed in the cylinder member around the portion 11 of the sleeve. Said sleeve is provided with transverse ports 37 communicating with the groove 36 and with the interior of the sleeve in advance of the piston. Two other annular grooves 38 and 39 are formed in the interior of the cylinder member 4 around the sleeve and are located in rear of the groove 36. These grooves 38 and 39 are in com-

munication with the interior of the sleeve by ports 40 and 41 formed in said sleeve. From the groove 38, a passageway 42 leads to the interior of the bushing 28, and from the 5 groove 39, a passageway 43 leads to and communicates with the interior of the bushing 29. The outer ends of these two bushings are closed by flanged plugs 44 that are held against rotation by pins 45 passing through 10 their flanges into the bushings. The bushings and closure plugs are held in place by a bolt 46 that passes longitudinally therethrough, being provided at one end with a head 47 pinned, as illustrated at 48 against 15 rotation, a nut 49, being threaded on the other end of the bolt and bearing against a spring 50 that in turn bears against the adjacent closure plug. The spring 50 preferably has enlargements 51 on its ends that 20 respectively engage in sockets in the nut 49 and the closure plug 44 to prevent the relative rotation of the parts. A reciprocatory distributing valve 52 is mounted in the bushings 28 and 29, and is slideable upon 25 the bolt 46, being provided with a central enlargement 53 that bridges the space between the inner ends of the bushings and being furthermore provided with end enlargements 54 that control the exhaust of 30 the motive fluid. To this end the said bushings are provided with exhaust ports 55 communicating with annular grooves 56 formed in the valve casing, and said grooves are in communication with an exhaust 35 chamber 57 shown more particularly in Fig. 2. The motive fluid is supplied to the distributing valve through a rotary throttle valve 58 having a channel 59 that is movable into and out of communication with a port 40 60 that leads to the space between the bushings 28 and 29.

Referring more particularly to Fig. 3, the 45 operation of the structure may be briefly outlined as follows:—With the valve in the position shown, motive fluid supplied through the throttle valve 59 and port 60 will enter between the bushings 28 and 29, and will find its way through the passage 35 to the annular groove 36. From this 50 groove, it will pass through the ports 37, into the sleeve in advance of the piston, and said piston will be driven rearwardly, the exhaust fluid escaping through the passageway 34, groove 26, ports 32, ports 35, groove 55 56, and from the exhaust chamber 57 into the open air. The piston moves rearwardly until it uncovers the ports 40 of the rotating chuck sleeve, whereupon motive fluid will 60 pass outwardly through said ports, through the groove 38 and passageway 42, into the bushing 28 in rear of the distributing valve 52. The valve will thereupon be moved to the right, whereupon the motive fluid will 65 enter the passageway 34, and thence into the cylinder member in rear of the piston,

driving said piston forwardly, the exhaust in advance of said piston now taking place through the ports 37, the groove 36, passageways 35, front ports 55, and groove 56 into the exhaust chamber 57. This forward movement continues until the annular groove 21 of the piston 20 uncovers the ports 41, the motive fluid behind the piston thence passing through the keyways 22, groove 21, ports 41, annular groove 39, and thus finding its way into the passageway 43. It will consequently be directed against the front end of the distributing valve, driving the same rearwardly and again reversing the direction of the movement of the piston. 75 80

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention. 90

Having thus fully described my invention, what I claim as new, and desire to secure by Letters Patent, is:—

1. In a motor of the character set forth, the combination with a cylinder member, of a rotatable sleeve in the cylinder member, a piston operating in the sleeve, means for delivering motive fluid through the sleeve to effect the back and forth movement of the piston, and means for rotating the sleeve from the piston. 95 100

2. In a motor of the character set forth, the combination with a cylinder member, of a rotatable chuck sleeve in the cylinder member, a piston operating in the sleeve, an automatic distributing valve, means for delivering motive fluid from the distributing valve through the sleeve to effect the back and forth movement of the piston, and means actuated by the piston for effecting a step-by-step rotation of the sleeve. 105 110

3. In a motor of the character set forth, the combination with a cylinder member, of a sleeve member rotatably mounted therein, one of said members having an annular channel, the sleeve having ports communicating with the channel and with the interior of the sleeve, a piston operating in the sleeve, means for delivering motive fluid from the piston to the annular channel, 115 and means associated with the rear portion of the piston and sleeve for effecting the automatic rotation of the latter from the former. 120

4. In a motor of the character described, 125 the combination with a cylinder member, of a sleeve rotatably mounted therein, a piston operating in the sleeve, means for supplying motive fluid to the piston to operate the same, an automatic distributing valve for 130

said motive fluid supply, and passageways leading from the cylinder member to opposite sides of the automatic valve, said sleeve having ports communicating with the passageways and alternately opened and closed by the piston during its movement.

5. In a motor of the character described, the combination with a cylinder member, of a sleeve member rotatably mounted therein, said members being formed with three annular channels between them, a reciprocating piston operating in the sleeve member, said sleeve member having sets of ports that respectively communicate with the said annular channels, the said piston alternately covering and uncovering two of the sets of ports, means for delivering motive fluid through the third channel and third set of ports against one end of the piston, a distributing valve for controlling such delivery, annular channels between them, a reciprocating and passageways leading from the other two channels to the opposite ends of the distributing valve.

6. In a motor of the character described, the combination with a cylinder member and a piston operating therein, of a chuck rotatably mounted in the cylinder member, means for rotating the chuck, slidably interlocked with the piston, means including an

automatic distributing valve for delivering motive fluid to the piston to actuate the same, and means for delivering motive fluid against the distributing valve to operate the same, said latter means being supplied through said interlocking connection between the piston and chuck rotating means.

7. In a motor of the character described, the combination with a cylinder member, of a rotatable sleeve in the cylinder member, a reciprocating piston operating in the sleeve and having longitudinally disposed keyways, means for effecting the rotation of the sleeve, engaged in the keyways and permitting the passage of fluid therethrough, said piston furthermore having an annular groove communicating with the keyways, and said sleeve having ports with which the groove communicates during the movement of the piston, a distributing valve, and a passageway leading from the ports to the distributing valve for conducting motive fluid against the same to operate it.

In testimony whereof I have hereunto set my hand in presence of two subscribing witnesses.
